UNITED STATES PATENT OFFICE

JOHN H. VOSS, OF CHICAGO, ILLINOIS, ASSIGNOR TO AUTOMATIC ELECTRIC INC., OF CHICAGO, ILLINOIS, A CORPORATION OF DELAWARE

AUTOMATIC TELEPHONE SYSTEM

Application filed October 18, 1926. Serial No. 142,245.

This invention relates in general to automatic telephone systems in which connections are established through the medium of subscriber-controlled automatic switches, but is more particularly concerned with such automatic telephone systems that include party lines and selective ringing equipment at the automatic exchange. The object of the invention is the provision of a new and improved automatic party-line selective-ringing connector switch for use in such systems.

In the past various kinds of automatic party-line frequency-selecting connectors have been used for establishing connections with party lines and for selectively signalling a particular party on the line. The most common of these is the type which employs a special frequency-selecting rotary switch mechanism which is operated responsive to a digit to select a particular frequency of ringing current to be used, and to determine the side of the line to which it is to be applied. The main feature of this invention is the production of a party-line frequency-selecting connector in which the frequency-selecting rotary switch mechanism is eliminated, and in which relays which are responsive to a digit dialled by the calling subscriber perform the function of selecting the frequency of ringing current and the line to which it is to be applied to selectively signal the desired party on a party line.

The foregoing object and the features of the invention will be described in detail in the following specification with the aid of the accompanying drawing, in which is shown by means of the usual schematic circuit diagrams the new and improved party-line frequency-selecting connector and sufficient of the apparatus associated therewith for a clear understanding of the invention.

In the drawing, the new and improved party-line frequency-selecting connector is indicated by the reference character C. Mechanically the connector C is of the well known Strowger vertical and rotary type having bank contacts arranged in horizontal rows or levels. The circuits of the connector C pertaining to the control of the line selection are also well known and will be described

only briefly; those pertaining to the selection of ringing current of a particular frequency and the application thereof to one or the other side of the line forms a particular part of this invention and will be described in detail hereinafter.

The connector C is one of a group of connectors accessible in the banks of a group of preceding selectors, connector C being accessible by way of the trunk line, comprising conductors 2, 3, and 4. In the banks of the connector C access is had to subscribers' lines, one of which is shown comprising conductors 110 and 111 terminating in bank contacts 101, 102, and 103, and serving substations A¹—A⁴, inclusive. At the exchange, the subscribers' lines also terminate in individual line switches, the line comprising conductors 110 and 111 terminating in the lineswitch RLS, which is of the well known rotary type.

The subscriber's substation A', shown in full, and the other three substations, only the ringers of which are shown, are of the regular automatic type, with their ringers connected from one or the other side of the line to ground as shown. For convenience, the exponents marking the substations have been assigned in accordance with the final digit to be dialled to signal each substation, as will be described in detail hereinafter.

The generators G¹ and G² are common to the exchange and supply ringing current of different frequencies. The busy machine B is also common to the exchange and supplies the busy tone current for giving calling subscribers the busy tone whenever connection is established with a busy line.

With this general description of the object of the invention and the apparatus shown in the drawing in mind, a detailed description of the operation thereof will now be given. For this purpose it will first be assumed that some subscriber wishes to converse with the subscriber at substation A¹. To establish this connection, the calling subscriber removes his receiver and dials the directory number of the subscriber at substation A¹. Responsive to the dialling of the first digits, automatic switches are successively operated, each switch operating to extend the connection to a

succeeding switch, the final switch to which the connection is extended being a connector. It may be assumed that in this manner the connection is extended by way of trunk conductors 2, 3 and 4 to the connector C.

When the connection is extended to connector C, a circuit is closed for line relay 11 which operates and closes a circuit for release relay 12. Release relay 12 operates and performs its usual operations, grounding the release trunk 3 at armature 27, grounding the holding conductor 100 at armature 28, and preparing the impulsing path at armature 29. Responsive to the dialing of the first of the last three digits of the called number, line relay 11 operates and sends a corresponding number of ground impulses to the vertical magnet 20, series relay 13 operating in series therewith. The operation of the vertical magnet 20 causes the switch wipers 71, 72, and 73 to be positioned opposite the proper level of bank contacts. At the end of this series of impulses, series relay 13 deenergizes and by releasing armature 33 extends the impulsing path to the rotary magnet 21.

Responsive to the dialling of the next digit of the called number, line relay 11 again operates and sends a number of impulses corresponding to the digit dialled to the rotary magnet 21, multiple relay 16 operating in parallel therewith. In operating, rotary magnet 21 positions the switch wipers 71, 72, and 73 into engagement with the bank contacts terminating the called line, these in this case being the bank contacts 101, 102, and 103.

If the line comprising conductors 110 and 111 is busy at this time, ground potential will be present on bank contact 102, causing the energization of the two windings of two-step busy relay 15 in series over the circuit including wiper 72 and armature 44 and its working contact. The busy relay 15 operates all its armatures and applies the busy tone current to the upper talking conductor at armature 38 and prepares the locking circuit for itself at armature 40, which is closed as soon as relay 16, which operated in parallel with the rotary magnet, releases its armature 44. The calling subscriber, hearing the busy tone, replaces his receiver. This initiates the release of the operated switches in the well known manner.

It may be assumed, however, that the line comprising conductors 110 and 111 is idle at this time. In this case relay 15 is not operated, and when relay 16 releases its armatures shortly after the cessation of impulses to the rotary magnet 21, a circuit is closed for the lower winding of switching relay 17, which may be traced from ground on the release conductor 3, resting contact and armature 39, through the lower winding of the relay 17, resting contact and armature 44, wiper 72, bank contact 102, through the

winding of switching relay 106 of the rotary line switch RLS, through the winding of the rotary magnet 107 to battery. The current flow over this circuit is insufficient to cause the operation of the stepping magnet 107, but relays 106 and 17 operate, relay 106 operating just sufficiently to disconnect the line conductors 110 and 111 from the normal battery and ground connections, and relay 17 operating to perform the following circuit changes: A ring back tone circuit is prepared at armature 48 and its working contact. A locking circuit is closed for the upper winding of relay 17 at armature 49. The short circuit around resistance 62 is opened at armature 50. At armature 51 direct ground potential is applied to the test contact 102 and the test contacts multiply connected therewith to mark the line to substation A' busy. At armature 52 and its working contact the impulsing path is extended to relay 15. At armatures 47 and 53 normally open points in the talking circuit are closed.

Since the subscriber at substation A¹ is the one with which conversation is desired, the final digit to be dialled is the digit 1. Responsive to the dialling of the last digit, which in this case is the digit 1, relay 11 again momentarily releases and sends one impulse of current over the impulsing path which now extends from armature 52 and the working contact, resting contact and armature 37, armature 42 and the resting contact, through the lower winding of two-step relay 15 to battery. The magnetic force produced by current in its lower winding is only sufficient to operate armature 40. By the operation of armature 40, a circuit is prepared for energizing the upper and lower windings of this relay in series, the upper winding, however, being short circuited during the time of the impulse. At the cessation of this impulse of current, ground potential is removed from the junction of the two windings of relay 15, so this relay is operated over its two windings in series. The magnetic force produced by current in the two windings causes the full operation of relay 15, its useful operation at this time being the preparation of the ringing circuit at armature 43 and the working contact. The ringing circuit is finally closed at armature 46 and the resting contact when relay 16, having energized in multiple with relay 15, deenergizes shortly after the cessation of the dialling of the digit.

The ringing circuit extends from the battery superimposed generator G', resting contact and armature 57, resting contact and armature 46, armature 43 and working contact, through the upper winding of ring-cut-off relay 14, resting contact and armature 34, working contact and armature 47, resting contact and armature 58, wiper 71, bank contact 101, conductor 110, through the ringer at substation A' to ground, and also through the ringer at substation A⁴.

to ground. The ringer at substation A⁴ is tuned so as not to respond to the frequency of ringing current from generator G', but the ringer at substation A' responds thereto and signals the called subscriber.

5 To answer the call, the subscriber at substation A' removes his receiver, and in so doing closes the direct current bridge across the conductors 110 and 111, thereby closing the direct current circuit for the upper winding 10 of the ring-cut-off relay 14, this circuit extending from battery superimposed generator G' to conductor 110 as traced above and then extending over the bridge at substation 15 A', conductor 111, bank contact 103, wiper 73, armature 61 and the resting contact, armature 37' and the working contact, armature 37' and the resting contact to ground. Ring-cut-off relay 14 operates over this circuit and 20 at armatures 34 and 37' completes the talking connection, closes the locking circuit for itself at armature 36, opens a point in the impulsive path at armature 37, and at armature 35 opens the locking circuit of relay 15. The 25 connection is now complete and conversation may take place between the calling and called subscriber.

At the termination of the conversation, the two subscribers replace their receivers, initiating the release of the operated switches as will be described hereinafter.

To further describe the operation of the connector C, it will be assumed that a calling subscriber wishes to engage in conversation 35 with the subscriber at substation A². To set up this connection, the calling subscriber again removes his receiver and dials the directory number of the subscriber substation A², which is the same number as the number 40 of substation A' except that the final digit is 2 instead of 1. It may again be assumed that the connector C is the one taken into use for establishing the connection. Connector C again operates responsive to the first two of 45 the last three digits to position its wipers 71, 72, and 73 in engagement with the bank contacts 101, 102, and 103, respectively, as described above.

Responsive to the last digit dialed by the 50 calling subscriber, which in this case is the digit 2, (assuming the line is again found idle) line relay 11 again intermittently deenergizes and sends two impulses of current, the first impulse being sent to relay 15 which relay operates all its armatures at the cessation of the 55 impulse and extends the impulsive path to the two-step wiper-reversing relay 19 by way of armature 42 and the working contact, and armature 60 and the resting contact. The 60 second impulse of this last digit then energizes the lower winding of two-step relay 19. The magnetic force produced by current in the lower winding of relay 19 is only sufficient to cause the operation of armature 59, which 65 prepares a circuit for energizing the two

windings of relay 19 in series, the upper winding being short circuited at this time by reason of the ground potential at the junction of the two windings. At the cessation of the impulse, however, this ground potential at the 70 junction point is removed and relay 19 is energized over its two windings in series. The magnetic pull produced by current flow in the two windings of relay 19 in series causes the full operation of this relay, thereby reversing the line wipers 71 and 73 as regards 75 their position in the ringing circuit at armatures 58 and 61, and extending the impulsive path to two-step relay 18 at armature 60. This latter operation is of no utility at this 80 time. Shortly after the cessation of the impulses of this digit, relay 16, having been energized in parallel with relays 15 and 19, successively, deenergizes and again closes the ringing circuit at armature 46. This time the 85 ringing circuit extends from the generator G' over a path similar to that traced above except that it now extends by way of the working contact and armature 61, wiper 73, back contact 103, line conductor 111, through the 90 ringers at substations A² and A³ to ground instead of over line conductor 110 through the ringers at substations A' and A⁴. The ringer at substation A³ is tuned so as not to respond to current from generator G'. The 95 ringer at substation A², however, responds to signal the subscriber at that substation. In response thereto, the subscriber at this substation removes his receiver, thereby placing 100 a direct current bridge across the line conductors, again causing the operation of the ring-cut-off relay 14. The return circuit for relay 14 this time includes conductor 110, bank contact 101, wiper 71, armature 58 and the working contact, to ground at the resting contact of armature 37'. Relay 14 operates as described in the previously described connection and completes a talking connection, whereupon the two subscribers may engage in 105 conversation. At the termination of the conversation, release of the operated switch is effected as will be described later.

It will now be assumed that the calling subscriber wishes to converse with the subscriber at substation A³. The calling subscriber dials 115 the directory number of the subscriber at substation A³ which is the same as that of the substation A¹ except that the last digit is 3 instead of 1. It will again be assumed that the connector C is taken for use. Connector C again operates responsive to the first two of the last three digits of the number to position its wipers 71, 72, and 73 on bank contacts 101, 102, and 103, respectively and tests the line for the busy or idle condition. Assuming 120 that the line is idle at this time, the subscriber dials the final digit 3. Relays 15 and 19 again operate successively responsive to the first and second impulses as described above. As 125 stated above, relay 19, in operating in its 130

second step, extends the impulsive path to relay 18 at armature 60. Therefore, the lower winding of relay 18 is energized by the third impulse. The magnetic pull produced by current in the lower winding of relay 18 is just sufficient to operate armature 54 which prepares a circuit for energizing the two windings of relay 18 in series, the upper winding being short-circuited during the time of the third impulse. At the cessation of this third impulse, ground potential is removed from the junction point of the two windings of relay 18, thereby permitting relay 18 to operate over its two windings in series causing the full operation of this relay. As a result, generator G² is substituted for generator G' at armature 57 and the working contact and the impulsive path is extended to relay 13 at armature 56. Again a ringing circuit is closed by the release of relay 16 at armature 46 shortly after the cessation of the third impulse. This ringing circuit is the same as that traced when the ringer at substation A² was operated except that the generator G² has been substituted for generator G'. The ringer at substation A² is tuned so as not to respond to current from generator G² but the ringer at substation A³ is tuned to respond to current from this generator. Thus, the subscriber at substation A³ is signalled. Removing the receiver at substation A³ to answer the call again causes the operation of the ring-cut-off relay 14 which interrupts the ringing circuit and completes the talking connection in the manner described previously. At the termination of the conversation release of the operated switches takes place as will be described hereinafter.

To describe how the subscriber at substation A⁴ is signalled, it will be assumed that a calling subscriber desires to converse with the subscriber at substation A⁴, and so dials his number which is the same as that of substation A' except that the final digit is 4. It may again be assumed that the connector C is taken into use and is operated responsive to the first two of the last three digits of the called number to position the wipers 71, 72, and 73 on bank contacts 101, 102, and 103, respectively, and test the line. Assuming the line is idle, again relays 15, 19, and 18 are respectively operated responsive to the first three impulses of the final digit which in this case is 4. As mentioned in the previous description, relay 18, in operating fully, extends the impulsive circuit to relay 13 at armature 56. Thus, the fourth impulse of the final digit traverses the impulsive path to the working contact and armature 56, winding of series relay 13, resistance 62, winding of vertical magnet, to battery. The current in the impulsive circuit is limited by the resistance 62 so the operation of vertical magnet 20 is prevented. Relay 13 operates, however, and at armature 32 opens the circuit of the two

windings of wiper-reversing relay 19. As a result, relay 19 deenergizes and again reverses the connections of wipers 71 and 73 back to normal as regards the upper and lower talking conductors. Now when relay 16 deenergizes shortly after the cessation of impulses, a ringing circuit is again closed over line conductor 110 to the ringers at substations A¹ and A⁴, this time from generator G² instead of generator G'. The ringer at substation A¹ is tuned so as not to respond to current from generator G², but the ringer substation A⁴ is tuned to respond to current from this generator, and therefore the subscriber at this substation is signalled. When the receiver at the substation is removed to answer the call, the ring-cut-off relay 14 is again operated and the talking connection is completed as previously described.

At the termination of the conversation the subscribers replace their receivers which initiates the release of the operated switches. At the replacement of the receiver at the calling station, line relay 11 deenergizes and opens a circuit release relay at 12. Release relay 12 deenergizes, removes the ground potential from release conductor 3 and holding conductor 100 at armatures 27 and 28, respectively, and also closes the circuit for the release magnet 22 at armature 29, off-normal springs 63 having closed upon the first vertical step of the switch wipers. The removal of ground from the release conductor 3 initiates the release of the previously operated switches, and the removal of ground from the holding conductor 100 opens the holding circuits of relays 14, 17, 18, and 19, causing the release of these relays. Relay 17, in releasing armature 51, removes ground potential from bank contact 102 thereby causing the release of relay 106.

This completes the description of the operation of this new and improved party-line frequency-selecting connector. What is thought new and is desired to have protected by Letters Patent will be specifically stated in the appended claims.

What is claimed is:

1. In a telephone system, a connector switch, party lines accessible thereto, means for operating said switch to select a line, a source of signalling current, a relay in said switch actuated responsive to one impulse of a series of impulses sent to said switch and deactuated responsive to another impulse of said series, and means controlled by said relay for applying said source of ringing current to either side of the selected line to signal either one of two parties connected to said line depending on the number of impulses in said series.

2. In a telephone system, a connector switch, party lines accessible thereto, means for operating said switch to select a line, a plurality of sources of ringing current, a first

and a second relay in said switch, said first relay being actuated responsive to one impulse of a series sent to said switch and de-actuated responsive to another impulse of said series, and said second relay being actuated responsive to another impulse of said series, and contacts on said relays for applying either of said sources of signalling current to either side of the selected line to signal 5 a particular party on said line depending on the state of operation of said relays as governed by the number of impulses in said series.

3. In a telephone system, a connector, 15 party lines, means for operating said switch to select a line, a first and a second source of signalling current, the first of said sources being normally adapted to be applied to one side of a selected line, a first relay actuated 20 responsive to one impulse of a series sent to said switch to adapt said first source to be applied to the other side of the selected line, a second relay actuated responsive to another impulse of said series for substituting said 25 second source for said first source, and a third relay actuated responsive to a third impulse of said series for deactuating said first relay thereby adapting the said second source to be applied to said one side of the selected line.

4. In a telephone system, party lines, a 30 two motion connector switch having access to said lines, means responsive to two series of impulses sent to said switch for operating said switch to select a line, said means including a relay operated during the primary motion of said switch to cause said switch to operate in its secondary motion, a source of signalling current, a wiper reversing relay for controlling the application of said signalling current to either side of the selected 35 line to signal a particular party on the selected line, means for causing said last relay to be actuated responsive to one impulse of a third series sent to said switch, and means for causing said first relay to be actuated 40 responsive to another impulse of said third series to deactuate said last relay.

5. In a telephone system, a party line, a 45 connector switch, means responsive to impulses sent to said switch for operating said switch to connect with said line, counting relays responsive to other impulses sent to said switch for selecting a particular party on said line, and circuit arrangements such that one of said counting relays also functions as a busy test relay.

6. In a telephone system, a party line having ringers connected to one or the other side of the line, a connector switch, means responsive to impulses sent to said switch for operating said switch to connect with said line, a plurality of sources of ringing current, and counting relays responsive to other impulses sent to said switch for selecting one of said 60 sources and for selecting the side of the line

to which the selected source is to be applied to signal a particular party on said line.

7. In a telephone system, party lines having ringers connected to one or the other side of the line, a connector switch for extending 70 connections to said lines, a plurality of sources of ringing current, and means consisting solely of relays for selecting a particular source of ringing current and the side of the line to which it is to be applied. 75

8. In a telephone system, a party line, a connector switch, means for operating said switch to connect with said line, a plurality of sources of ringing current, and counting 80 relays for selecting one of said sources and for selecting the side of the line to which the selected source is to be applied to signal a particular party on said line, each of said relays being responsive to an impulse sent to said switch and one of said relays being responsive to two impulses sent to said switch, 85 the source selected and the side of the line to which it is to be applied depending on the number of impulses sent to said switch.

9. In a telephone system, a line, a plurality 90 of stations on said line, a connector switch, means for operating said switch to connect with said line, and counting relays less in number than the number of stations on said line and responsive to impulses sent 95 to said switch for selecting any station on said line, the particular station selected depending on the number of impulses sent to said switch.

10. In a telephone system, a line, a plurality 100 of subscribers' stations on said line, a connector switch, means for operating said switch to connect with said line, a plurality of sources of ringing current, and counting relays less in number than the number of stations on said line and responsive to impulses sent to said switch for selecting one of said sources and a side of the line to which it is to be applied to signal any one of the subscribers on said line, the particular subscriber 105 signalled depending on the number of impulses sent to said switch.

11. In a telephone system, a connector switch, a line, means responsive to impulses sent to said switch for operating said switch 110 to connect with said line, a source of signalling current, and a busy test relay in said switch operative responsive to the establishment of the connection providing the line is busy, and responsive to another impulse sent 115 to said switch providing said line is idle for applying said source to said line.

12. In a telephone system, a line, means for establishing a connection with the line, a source of signalling current, and a relay 120 responsive to the establishment of said connection for giving a busy signal, providing the line is busy, and responsive to an impulse sent to said relay for applying said source to said line, providing the line is idle. 125 130

13. In a telephone system, a calling line, a called line, means for establishing a connection from said calling line to said called line, a source of signalling current, a relay 5 automatically responsive to the establishment of said connection for giving a busy signal, providing the called line is busy, and means controlled over the calling line for operating said relay to apply said source to said called line, providing the called line is idle.

14. In a two motion party line connector, a changeover relay, counting relays for controlling selective ringing, and circuit arrangements whereby said changeover relay is used as a counting relay in order to reduce the total number of relays required.

15. In a two-motion party line connector, a busy test relay, counting relays for controlling selective ringing, and circuit arrangements whereby said busy test relay is used as a counting relay in order to reduce the total number of relays required.

16. In a two-motion party line connector, 25 a changeover relay, a busy test relay, counting relays for controlling selective ringing, and circuit arrangements whereby said changeover relay and said busy test relay are both used as counting relays in order to reduce the total number of relays required.

17. In a telephone system, a two motion switch having wipers, a changeover relay, a wiper reversing relay responsive to an impulse of current sent to said switch, and 35 means for causing said first relay to be actuated responsive to another impulse of current sent to said switch to deactuate said wiper reversing relay.

18. In a telephone system, a party line having ringers connected to one or the other side of the line, a connector switch for extending a connection to said line, a plurality of sources of ringing current, counting relays responsive to impulses sent to said switch, 40 means controlled by one of said counting relays for selecting one of said sources, and means controlled by another of said counting relays for selecting the side of the line to which the selected source is to be applied to signal a particular party on said line.

19. In a selective ringing device, a relay energized responsive to one impulse of a train, means for deenergizing said relay responsive to a subsequent impulse of the train, 55 provided the train includes enough impulses, whereby the condition of the relay at the end of the train of impulses depends on the number of impulses in the train, a ringing circuit controlled by said relay when energized, and a different ringing circuit controlled by said relay when deenergized.

20. In a party line connector having two movements to select a line, a change-over relay for controlling the shift from the first 60 movement to the second, counting relays

operated by a train of impulses separate from the setting impulses, one of said relays being energized responsive to a particular train to select a particular party, means for operating said change-over relay responsive to a different train, and means for deenergizing said energized counting relay responsive to the operation of said change-over relay to select a different party.

21. In a two-motion switch, a change-over relay, a series of counting relays, and a locking circuit for one counting relay controlled by said change-over relay.

22. In combination, a series of counting relays, means for energizing said relays one after the other responsive to successive impulses of a train, another relay energized responsive to another impulse of the train, and means for deenergizing one of said counting relays responsive to the energization of said other relay.

23. In combination, a plurality of counting relays, said plurality consisting of not less than three relays, means for successively energizing said relays responsive to a like plurality of impulses in a train, and means for deenergizing one of said relays in case the number of impulses in the train exceeds the number of counting relays.

24. A counting relay arrangement as set forth in claim 23, in which the counting relays constitute a series as regards the order in which they are energized and in which the relay which is deenergized is an intermediate relay of the series.

In witness whereof, I hereunto subscribe my name this 14th day of October, A. D., 1926.
